(57) **CLAIM**

The ornamental design for a pintle hook assembly, as shown and described.

DESCRIPTION

FIG. 1 is a perspective view of a pintle hook assembly; FIG. 2 is an elevational view of a left side of the pintle hook assembly;

FIG. 3 is an elevational view of a right side of the pintle hook assembly;

FIG. 4 is a front elevational view of the pintle hook assembly;

FIG. 5 is a rear elevational view of the pintle hook assembly;

FIG. 6 is a top plan view of the pintle hook assembly; and,

FIG. 7 is a bottom plan view of the pintle hook assembly. The dashed lines within the figures are shown for illustrative purposes only and form no part of the claimed invention.
